(57) **CLAIM**

The ornamental design for goggle strap, as shown and described.

DESCRIPTION

FIG. 1 is a perspective view of goggle strap showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof; and,

FIG. 8 is an additional reduced perspective view thereof.

The broken-line disclosure in the view is for illustrative purposes only and forms no part of the claimed design.

1 Claim, 5 Drawing Sheets
